CLAIM

The ornamental design for a salvage drum, as shown and described.

DESCRIPTION

FIG. 1 is a side elevation of a salvage drum showing our new design, the opposite side being the same in appearance;

FIG. 2 is a top view thereof;

FIG. 3 is a perspective view thereof;

FIG. 4 is a bottom view thereof; and

FIG. 5 is a fragmentary cross section showing a detail of the salvage drum.

FIG. 1

FIG. 2

FIG. 3

FIG. 4

FIG. 5
